(57) **CLAIM**

The ornamental design for an air freshener for vehicles, as shown and described.

DESCRIPTION

1. Air freshener for vehicles

1.1 : Perspective

1.2 : Front

1.3 : Right

1.4 : Left

1.5 : Back

1.6 : Perspective

1.7 : Top

The design consists of an air freshener for vehicles comprising a clip and a rectangular diffuser body with a diamond-shaped section; figure 1.1 is a perspective view of the design for which protection is claimed; figure 1.2 is a front view thereof; figure 1.3 is a right-side view thereof; figure 1.4 is a left-side view thereof; figure 1.5 is a back view thereof; figure 1.6 is a perspective view thereof; figure 1.7 is a top view thereof.

The broken lines depict portions of the air freshener for vehicles that form no part of the claimed design.
